UNITED STATES PATENT OFFICE

WILLIAM FORSTNER, OF IRVINGTON, NEW JERSEY, ASSIGNOR TO FORSTNER CHAIN CORPORATION, OF IRVINGTON, NEW JERSEY

FLEXIBLE METALLIC STRAP

Application filed May 1, 1929. Serial No. 359,573.

This invention relates to improvements in ornamental chains of a type used for bracelets, watch fob supports, wrist watch bands and sundry other articles of personal wear and adornment where a thin, flexible, fine appearing linked structure is desirable.

One of the objects of this invention is to provide a chain having the foregoing characteristics and which includes beauty and strength in a high degree.

A further feature is in the provision of a flat ornamental chain composed of a single series of embossed rectangular plates produced from sheet metal by ordinary stamping operations and connected in pairs by series of narrow links overlying the depressed portions of the plate, producing the appearance of a chain having a series of links arranged in parallel rows, in which each alternate link is arranged in uniformly staggered relation.

Other objects will appear in the following detailed description of the structure, reference being had to the accompanying drawing, in which:

Figure 1 is a front face view of a portion of chain made in conformity with the invention.

Figure 2 is a bottom view of the same.

Figure 3 is an enlarged fragmentary sectional view taken on line 3—3 of Figure 1.

Figure 4 is a perspective view of one of the plate links in detail.

The main portion of the chain is composed of a plurality of substantially rectangular plate links, stamped or rolled from metal to produce a series of ribs 6 extending along the faces of the blanks, these ribs being generally elliptical in cross section, uniformly spaced apart in parallel to extend the full length of the blank and are equally raised on both faces of the blank, four being shown although obviously a greater or lesser number might be used.

Intermediate the ribs 6 are thin flat integral connections 7, appearing as channels on

each side and having in their end portions small rectangular perforations 8—8', reaching across adjacent edges of the ribs, these blanks, when assembled, presenting narrow spaces 9 between adjacent members.

The connecting links 10 are semi-elliptical in cross section, their convex sides being outermost, while their flat under sides are seated on the corresponding flat surfaces of the channel-like connections 7.

The links 10 are bent to present re-entrant loops 11—11', disposed respectively in the perforations 8 of two adjacent plate elements, the loop 11' having a continuing element 12 disposed in parallel to the element 10 on the underside of the connections 7, to terminate in an inbent prong 13 disposed in the perforation 8.

The other loop 11 has a similar but shorter reentrant turned member 14 to seat on the channel portions of the two contiguous plate links and terminates in a prong 15 entering the perforation 8 alongside the mating prong 13, thus linking the plate members securely but loosely together.

It is to be seen that the combined thickness of the elements 10, 7 and 12, or 10, 7 and 14 are essentially equal to the thickness of the ribs 6, so as to present a substantially level surface on both sides of the chain, which appears on its face as if composed of uniform links arranged in alternate staggered relations, while on the under side the links intermediate the ribs appear to be of two different lengths, the shorter of which are the connecting elements.

Due to the choice of metal finish which can be used the links may be of a color contrasting to the ribs, or enamel may be employed if desired.

The structure is obviously possessed of great strength, and by reason of the arrangement of the connecting elements, any desirable degree of flexibility may be obtained.

The foregoing disclosure is to be regarded

as descriptive and illustrative only, and not as restrictive or limitative of the invention, of which obviously an embodiment may be constructed including many modifications
5 without departing from the general scope herein indicated and denoted in the appended claims.

Having thus described the invention, what is claimed as new and desired to secure by
10 Letters Patent, is:—

1. An ornamental chain composed of plates embossed to present a series of longitudinal ribs extending equally on both faces and having thin flat connections therebetween, said
15 connections being perforated in their end portions, links disposed on said connections, loops formed on said links to engage the perforations at one of the ends of said connections, re-entrantly turned elements extending from said loops to seat on the opposite faces of said connections, and prongs on the extremities of said re-entrant elements to engage the perforations in the opposite ends of said connections.
- 25 2. An ornamental chain composed of a plurality of duplicate plates channeled longitudinally to present a series of ribs uniform on both faces of the plates, said channels having perforations near their ends, links seated in the channels to pass through the perforations in contiguous links whereby they are held in endwise relation, and means on the terminals of said links to lockingly engage in other perforations in said channels.
- 35 3. An ornamental chain composed of plates embossed to present a series of longitudinal ribs of elliptical cross section having thin flat connections therebetween, said connections being perforated near their ends, links of semi-elliptical cross section having their flat surfaces seated on said connections and being bent to engage in the end perforations of each succeeding plate, the ends of said links being turned inwardly to engage in the perforations in the other ends of said plates.
- 40 4. An ornamental chain composed of plates embossed to present a series of equally spaced ribs of elliptical cross section integrally joined by thin flat members containing openings in their end portions, and links bent to engage in one of the end openings in two adjacent plates to extend over said flat members on both sides thereof, said links having
45 terminals to enter the other of the end openings, said links being of a cross section corresponding to said ribs.

In testimony whereof I have hereunto affixed my signature.

WILLIAM FORSTNER.
